(57) **CLAIM**

The ornamental design for a handle as shown and described.

DESCRIPTION

FIG. 1 is a first isometric view of a handle;

FIG. 2 is a second isometric view of the handle;

FIG. 3 is a third isometric view of the handle;

FIG. 4 is a fourth isometric view of the handle;

FIG. 5 is a front elevational view of the handle;

FIG. 6 is a left side view of the handle;

FIG. 7 is a rear elevational view of the handle;

FIG. 8 is a right side view of the handle;

FIG. 9 is a top plan view of the handle; and,

FIG. 10 is a bottom plan view of the handle.

The broken lines in the Figures show portions of a handle that form no part of the claimed design.
